UNITED STATES PATENT OFFICE.

CALVIN KEELER, OF HOBART, NEW YORK.

DEVICE TO PREVENT RAILROAD-RAILS FROM SPREADING.

SPECIFICATION forming part of Letters Patent No. 445,449, dated January 27, 1891.

Application filed June 13, 1890. Serial No. 355,274. (No model.)

To all whom it may concern:

Be it known that I, CALVIN KEELER, a citizen of the United States, and a resident of Hobart, in the county of Delaware and State of New York, have invented certain new and useful Improvements in Devices for Preventing Railroad-Rails from Spreading; and I do hereby declare that the following is a full, clear, and exact description of the invention, which will enable others skilled in the art to which it appertains to make and use the same, reference being had to the accompanying drawings, which form a part of this specification.

My invention relates to improvements in devices for preventing railroad-rails from spreading, and also more effectually holding and retaining the fish-plate in position, whereby the safety of the trains running on the rails is enhanced.

One of the chief causes of railway accidents is due to what is termed "spreading of the rails"—that is, they are forced apart—causing the cars to jump the track. This spreading is particularly liable to occur on curves and in bad weather, and is frequently the cause of serious accidents.

The object of my invention is to provide a simple and economical device, in which the rails are securely held and prevented from spreading or displacement under ordinary circumstances. The improved construction also provides for holding the fish-plates at the joints securely, and also acts as a nut lock for locking the nuts of said fish-plates.

The invention consists in the novel construction and combination of parts hereinafter fully described, and definitely pointed out in the claim.

In the accompanying drawings, Figure 1 is a cross-sectional view of a railroad constructed in accordance with my invention. Fig. 2 is a plan view of the same. Fig. 3 is a perspective view of the retaining-plates detached.

In the said drawings, the reference-number 1 designates the ties, and 2 the rails. These may be of any ordinary or suitable construction.

The numeral 4 designates fish-plates for connecting the adjoining ends of two rails, said plates being located on both sides of the rails and secured by means of bolts 6 and nuts 7.

The numerals 8 and 9 designate retaining-plates for holding the rails and serving to prevent them from spreading. These plates have their outer ends bent over, forming grips 10, which embrace or engage with the webs of the rails, and they extend to about the center of the track, where their inner ends are angularly bent, forming projections 12, through which pass bolts 13, secured by nuts 14. For the purpose of forming a nut-lock these plates may have their outer ends also bent upwardly, forming projecting portions 15, which are recessed or cut away at 16, so as to engage with the nuts 7 of the bolts 6 and prevent them from turning, whereby the fish-plates are securely held in place. The device also acts as a brake to prevent the rails from tipping over.

From the above it will be seen that an efficient and reliable device is provided for preventing the rails from spreading, which in practical use will be found to be of great value and importance.

Having thus described my invention, what I claim is—

In a railroad, the combination, with the rails 2, the fish-plates 4, the bolts 6, and nuts 7, of the retaining-plates 8 and 9, connected together at their inner ends, and their other ends provided with grips to engage the rails, and with upwardly-projecting portions 15, recessed at 16, to engage with and lock the nuts of the fish-plates, substantially as described.

In testimony that I claim the foregoing as my own I have hereunto affixed my signature in presence of two witnesses.

CALVIN KEELER.
